United States Patent Office

Des. 175,845
Patented Oct. 18, 1955

175,845

CONVERTIBLE PASSENGER AUTOMOBILE OR SIMILAR ARTICLE

Edward R. Macauley, Grosse Pointe Farms, Mich., as signor to Studebaker-Packard Corporation, a corporation of Michigan

Application May 11, 1953, Serial No. 24,937

Term of patent 14 years

(Cl. D14—3)

Figure 1 is a front perspective view of a convertible passenger automobile or similar article embodying my new design; and

The characteristic features of my design reside in the portions shown by means of full lines in the drawings.

I claim:

The ornamental design for a convertible passenger automobile or similar article, substantially as shown and described.
